CLOSURE DEVICE FOR RENDERING
BOTTLES NONREFILLABLE

Walter A. Stattmann, Chicago, Ill.

Application February 1, 1935, Serial No. 4,423

1 Claim. (Cl. 215—30)

The invention relates to a closure device adapted to be mounted upon the discharge end of a bottle or other receptacle for rendering such bottle or receptacle incapable of being refilled after the contents thereof have been exhausted.

The main object of the present invention is to provide a simple, relatively inexpensive and efficient device of this character, wherein refilling of the bottle equipped with the closure device is incapable of being accomplished, either mechanically or by the employment of vacuum means for first exhausting air from the bottle and then causing the same to refill itself by reason of such vacuum.

A further object of the invention is to provide a closure device of the character set forth which, per se, is assembled at the place of manufacture and which is shipped in assembled form to the distillers or bottlers for mounting of same on the bottle in the condition in which the device is received from the factory.

Further objects of the invention relating to specific advantages and characteristics of the structure of the present invention will be pointed out in or fully understood from the following specification:

The invention may be embodied variously and several embodiments thereof are illustrated in the accompanying drawings, wherein,

Fig. 1 is a fragmentary, vertical, longitudinal section of the upper or discharge end portion of a bottle neck equipped with a closure device constructed in accordance with the present invention, the said device being shown in central, longitudinal section.

Fig. 2 is a plan sectional view of the same taken on the line 2—2 of Fig. 1.

Fig. 3 is a plan sectional view taken on the line 6—6 of Fig. 1.

Fig. 4 is a view in side elevation of one of the valves employed in the structure, the same being shown partly in section.

Figs. 5 and 6 are perspective views of the said valve.

Fig. 7 is a perspective view of another of the valves employed in the structure, the same being shown partly in section.

Fig. 8 is a view similar to Fig. 1 showing another or modified embodiment of the invention.

Fig. 9 is a plan section of the same taken on the line 9—9 of Fig. 8.

Fig. 10 is a view similar to Fig. 8 illustrating another modification of construction of the device.

Fig. 11 is a plan sectional view on the line 11—11 of Fig. 10.

It has been attempted heretofore to render bottles non-refillable by applying thereto valved closure devices of which there are many examples in the art, made of various materials and wherein a gravity operated valve similar to a check valve is employed to prevent refilling of the bottle and wherein the valve has been rendered inaccessible to a wire or other tool to maintain the same off its seat during bottle refilling operations.

The valves of prior art structures also have been relied upon to prevent the refilling of the bottle by the very common expedient of inverting the bottle equipped with the closure device in a sealed tank containing a given level of the liquid to be introduced into the bottle and then, by applying vacuum pump to the tank, exhausting the air from the same and likewise, of course, from the inverted bottle until a very high degree of vacuum, as for example, equal to thirty degrees of mercury, has been obtained.

During this operation the neck of the bottle remains immersed in the liquid and upon admitting air to the tank so that atmospheric pressure is restored gradually, the said liquid is caused to flow into the bottle in an obvious manner while the valve controlling the discharge port of valve structure is maintained off its seat by gravity or by mechanical means.

Many of the prior art closure devices have been successfully constructed so as to prevent access to the valve by a wire or other device for the purpose of holding it from its seat during refilling operations, but few, if any have been able to defeat the success of the above-described method of effecting discharge of liquid from the bottle that the valve controlling the discharge port shall open very easily and to that end a very light valve which reseats by gravity upon restoring the bottle to upright position has been required.

In the instance of the present invention the filling of the bottle by resorting to the aforesaid vacuum method as well as by merely mechanically maintaining the valves from their seats is obviated as will appear more particularly by reference to the drawings and from the following description. Where means for preventing access to the valve have been proposed, the freedom of flow from the bottle has been reduced to such an extent as to defeat in large measure all the advantages of the structure. To provide an effective closure of the

type to which the invention relates which assures free discharge from the bottle constitutes another object of the invention.

The closure device comprises an outer sheet metal cap (1) which normally comprises a substantially cylindrical skirt portion terminating at its upper end in an inwardly projecting annular flange (2) bordering a central opening (3). Mounted within said cap or shell (1) is a valve casing (4) composed preferably of a suitable vitreous material such as glass or porcelain. Said valve casing is cylindrical and preferably is open at its lower end. It is equipped at its upper end with a discharge spout (5) which is concentric with the body or circumferential wall of said casing. Projecting inwardly from the said circumferential wall of the casing is a series of equal spaced-apart longitudinal ribs (6) extending radially from and which are integral with said circumferential wall and also, at their upper ends, with the top wall (7) of the valve casing. Said ribs are of greater length radially at their upper than at their lower ends, or in other words, have inner edges which converge toward each other from the lower end of the casing to the lower face of the upper wall (7) of the same. It will be noted that the said inner edges of the ribs (6) are disposed outwardly of the orifice of the discharge spout (5) and are normally spaced from the circumferential face of the valve (8), which consists of a truncated cone, the base of which is adapted to rest upon a washer or disk (9) which constitutes a removable bottom wall for the valve chamber and a seat for the valve. In the instance illustrated, the said bottom wall disk or washer (9) bears against the annular shoulder (10) between the thicker upper end portion of the circumferential wall of the valve chamber and the thinner lower end portion (11) of said wall. The length of the said thinner portion is greater than the thickness of the disk or washer (9) and is adapted to receive the upper annularly flanged portion (12) of the second valve casing (13) which is also cylindrical and projects in part into the neck (14) of the bottle. The valve casing (13) is also composed preferably of a vitreous material such as glass or porcelain and is open at its upper end so that the disk or washer (9) constitutes the upper wall of said valve chamber (13) which communicates with the valve casing (4) through the central orifice (15) of said disk or washer (9).

In the bottom wall (17) of the casing (13) there is a central opening (18) through which liquid contained in the bottle is discharged into the valve chamber of the casing (13) and thus into the valve chamber of the casing (4) and thence through the discharge spout (5). Mounted on the lower wall of the chamber of casing (13) is a washer (19) which may be composed of cork or other relatively soft material which forms a seat for the valve (20). The latter also is composed preferably of glass or other vitreous material and is sufficiently light or of a specific gravity so low as to enable the same to be moved easily to its seat, when the bottle is inverted, by flow of fluid into the bottle through the closure structure.

As shown in Figs. 3, 4, and 5, the said valve (20) comprises a cylindrical base portion (21) which is equipped with a bottom recess (22) and which, at the top, presents a plurality of equal and equally spaced radial ribs (23) which define the upper ends of recesses in the valve structure which presents what might be termed

stream-line walls leading from the said upper end of the ribs (23) to the base (21) at points quite closely adjacent to the lower face of the latter, said stream-line contour of the walls of said recess being important to effect a free flow of liquid from the bottle when the latter is inverted for purposes of discharge of liquid therefrom, the free flow from the bottle being extremely desirable in structures of the type to which the invention relates and the accomplishment whereof constitutes an object of the present invention. To promote such free flow the intake ends of the several ports through which liquid passes from the bottle are provided with well rounded corners.

The length or height of the valve (20) is only slightly less than that of the chamber in which it is contained and the diameter of the openings opposed to upper ends of the valves are such that no part of a valve will project into such an opening in any position of a valve in its chamber. Upon inverting the bottle for purpose of discharge of liquid from the latter, the said valve will tilt up or move partly from its seat to permit the flow of liquid through the said valve chamber and into the valve casing (4). The inversion of the bottle results also in causing the valve (8) to move from its seat and thereupon the liquid passing through the central orifice (15) will flow through the recesses between the ribs (6) and around the valve (4) and thus through the discharge spout (5), it being noted that when the valve (8) is completely engaged by the inner edges of the ribs (6) there is still ample room for flow of liquid past the upper or outer face of said valve.

One of the main advantages derived from the employment of two valves and two valve chambers arranged as illustrated is that access to the valve in the lower chamber by means of a wire or other device, is prevented so that even though the outer valve is held from its seat mechanically, the action of the inner valve cannot be interfered with to permit refilling of the bottle.

In Figs. 8 to 11, inclusive, the structures are illustrated as modified to the extent that both valves employed therein are identical with the structures of Figs. 3, 4, and 5 inclusive. In instances where the device is made of porcelain, cementing said bottom wall to the circumferential wall of the valve casing prior to baking the structure, causes said bottom to become substantially integral with the circumferential wall, the valve being inserted after drying of the valve casing (24) and before said bottom wall (25) is mounted in place.

In the instance of the present structures of Figs. 8 to 11 inclusive, the bottom wall (25) may consist of disk of any kind of material similarly to the disk (9) of Fig. 1, or the disk (26) may be of a diameter as great as that of the casing (24). If said disk (26) is composed of a flexible material, it may be of greater diameter than the inner diameter of the shell (1) and thus afford another fluid tight joint in the assembly of the component elements of the complete structure.

The lower valve casing (27) has a cylindrical wall equipped at its upper end with an outwardly extending annular flange (28) which bears against the washer (26) or against the lower end of the casing (24). Said casing (27) is also provided with a lower inwardly extending annular flange (29) upon which a valve seat

washer (30) of suitable flexible material such as cork, is used.

The operation of the structure of Figs. 8 to 11 inclusive, is substantially identical with that of the structure of Fig. 1 so that a repetition of description of operation will not be required.

In the several embodiments shown, the valve casings are slipped into the cylindrical shell of the cap (1) and a packing washer (31), of cork or other suitable material, having a central opening of slightly less diameter than the outer diameter of the casings (13) and (27), respectively, is forced over said casings to bear against the annular flange at the upper end of each thereof so as to firmly engage said casing. The said washer is also of appreciably greater outer diameter than the inner diameter of the shell of the cap (1) so that it must be crowded into the latter under a very appreciable degree of force or pressure and thus serves to hold the several casings very firmly in proper relative positions within the said cap before the structures are mounted on the bottle neck.

The structures are shipped from the factory to the bottling establishment in their completely assembled condition and, upon receipt of the same, are mounted on the bottles by inserting the bottle neck into the mouth portion of the shell of the cap (1) and applying pressure to vertically compress the said washer (31) and to maintain the same compressed while the mouth portion of the skirt of the cap is spun or otherwise contracted to engage in the annular bead (33) which borders the bottle mouth.

The several valves of the structures are rendered as hollow as possible and are of such specific gravity that they will be moved easily to their seats responsively to flow of liquid into the bottle as hereinbefore described and thus any attempt to refill bottles after exhaustion of the original contents will be defeated and this is rendered particularly true by reason of the fact that the soft seat for the valve in the inner valve casing of each structure permits said valve to hermetically seal the bottle without requiring opposed ground surfaces to be provided.

The soft valve seat of the inner valve casing is of a slightly larger diameter than the inner diameters of the casings in which it is received and is forced into place and held there by friction.

In the manufacture of the structures of Fig. 1 and Fig. 8, respectively, wherein the valve casings are composed of porcelain or similar vitreous material, the valve casings and valves are dried preparatory to entry into the kiln and with respect to the outer valve casing and the disk constituting the bottom closure thereof, a thin film of moist clay may be disposed between the opposed surfaces after the valve has been inserted. This forms a bond which renders said casing and disk substantially homogeneous with each other in the firing.

The necessity of providing a soft seat for the valve of the inner valve casing requires that the latter be fired before the seat washer is inserted but thereafter said inner valve chamber, particularly in the case of the structure of Fig. 1, is

substantially welded to the outer valve casing by means of an oxyacetylene flame jet impinging upon the meeting edges of the flange of the inner casing and the surrounding portion of the circumferential wall of the outer casing, this 5 operation being accomplished very quickly to produce two or three spaced apart spot welds.

Resort to the foregoing method of producing a completely assembled valved structure at the pottery is very advantageous as it prevents loss 10 or displacement of component parts thereof in the event that the packing washer which assembles said structure with the metal cap should fail to hold the parts in assembled relation in transit from the factory to the bottling plant. 15

It will be noted also that the valve controlled openings of the valve casings are rounded at their intake corners for cooperation with the valves of the types shown to promote free flow of liquid from the bottle. The diameter of said 20 openings is so much smaller than that of the valves below the same as to obviate all possibility of a valve projecting in part into such an opening in event that it becomes tilted in moving from its seat and thus possibly becoming caught or jammed against reseating.

It will be noted that the valve in the upper chamber of Fig. 1 will move by gravity to closed position, by cooperation with the ribs of said chamber, before, or just about the time that the 30 bottle reaches a substantially horizontal position when the same is being restored to upright position. This is advantageous in preventing refilling of the bottle.

I claim as my invention:

Mechanism for rendering a bottle non-refillable comprising a cap, the latter and the bottle equipped with inter-engaged formations for permanently securing said cap upon the bottle, a cup of vitreous material equipped with a peripheral flange along its rim and with a central opening in its bottom wall, a packing washer disposed between said flange and the rim of the bottle mouth, a gravity actuated valve in said cup for maintaining the said opening normally 40 sealed, said valve being of small diameter than said cup and capable of lateral movement therein, said valve equipped at its upper end with a plurality of radial ribs defined by radial recesses each presenting a continuous concave 45 surface vanishing in an upper V-shaped surface at the junction of said ribs and extending at a downward incline to a point adjacent the bottom surface of said valve and being of sharply increasing width progressively from the middle 50 portion to the peripheral surface of said valve, a disk having a central opening disposed over said cup and spaced therefrom a distance substantially greater than the height of said valve and confining the latter within said cup, a second 55 similar valve mounted upon said disk, an inverted cup member equipped with a central discharge spout at its upper end and cooperating with said disk to effect confinement of said second valve similarly to said first-named valve, 60 said respective cups being mounted within said cap.

WALTER A. STATTMANN.
